and apparatus for irrigating land, and particularly to a valve for automatically venting air and gas from irrigation systems.

It is an object of the present invention to provide an improved valve for automatically venting air and gas from irrigation systems.

UNITED STATES PATENT OFFICE

2,603,493

AUTOMATICALLY VENTED LIQUID FLOW REGULATING VALVE

Carlo F. Rusconi, Fresno, Calif.

Serial No. 142,558

Application February 6, 1950, Serial No. 142,558

5 Claims. (Cl. 277—8)

1. The present invention relates to valves and

more particularly to a valve adapted to regulate liquid flow by adjustment thereof and automatically to emit therethrough any air or gas carried by such a liquid.

Farming in arid regions requires frequent irrigation of the soil. It is the usual practice to conduct water from a source thereof, such as a well or reservoir, to areas requiring water, through concrete or tile aqueducts. Whether the conducting of the water is by pressure or gravity flow, air and well gas frequently collects in the aqueducts forming so-called vapor locks therein. Further, such air and gas tends to seek out and to enlarge pores, cracks and the like in the aqueducts, causing rapid deterioration thereof. Because of the difficulties incident to the collection of air and gas, it is usually necessary for a custodian frequently to bleed the aqueducts by manually opening widely dispersed valves in the irrigation system. This is not only a time-consuming and expensive procedure but it is not always effective in that it is impossible to anticipate accurately the portions of the aqueducts most needing such bleeding at any given moment.

In an effort to solve these problems, farmers have provided elevated standpipes which extend to a sufficient height to permit their continuous opening to the atmosphere without overflow of water. Obviously, such an expedient cannot be employed in pressure systems because of the excessive heights required and in gravity systems has the disadvantage of providing an obstruction occupying space more advantageously employed for other purposes. Further, such standpipes or vents, are subject to frequent damage by being struck by tractors and implements drawn thereby.

It is an object of the present invention to provide an improved valve adapted to exhaust air and gas therethrough while effectively regulating or blocking flow of liquid.

A further object is to provide means for bleeding air and gas from subterranean irrigation systems and the like which need not be extended appreciably above the surface of the soil to accomplish its intended purposes.

Other objects are to provide a valve of the character and for the purposes set forth that is fully effective in its operation, economical to produce, readily adapted to conventional irrigation aqueducts and systems, and durable in structure.

Still further objects and advantages of the present invention will become apparent in the subsequent description in the specification.

1. A valve for automatically venting air and gas from irrigation systems, comprising a valve body having an air and gas bleed valve and a water flow regulating valve, the bleed valve being supported internally of the valve body by a ring secured coaxially in an outlet, the ring being secured by forming an annular rib on the periphery of the ring which rests on a shoulder formed in the outlet, a seal of cement or the like filling the space between the ring and the interior of the outlet above the rib securing the ring in place, a cylindrical boss supported coaxially of the ring near its lower end by means of a spaced spider extending radially between the ring and boss, the boss being provided with a coaxial internally screw-threaded opening, a circular valve plate having an outer diameter slightly larger than the outer diameter of the ring being adapted to seat against the upper edge of the ring which is machined or ground to a smooth valve seat, a screw-threaded stud

extending through the valve plate and the ring into the interior of the valve body, the stud being secured to the valve body and being threaded into the screw-threaded opening of the boss.

2. A valve for automatically venting air and gas from irrigation systems, comprising a valve body having an air and gas bleed valve and a water flow regulating valve, the bleed valve being supported internally of the valve body by a ring secured coaxially in an outlet, the ring being secured by forming an annular rib on the periphery of the ring which rests on a shoulder formed in the outlet, a seal of cement or the like filling the space between the ring and the interior of the outlet above the rib securing the ring in place, a cylindrical boss supported coaxially of the ring near its lower end by means of a spaced spider extending radially between the ring and boss, the boss being provided with a coaxial internally screw-threaded opening, a circular valve plate having an outer diameter slightly larger than the outer diameter of the ring being adapted to seat against the upper edge of the ring which is machined or ground to a smooth valve seat, a screw-threaded stud

extending through the valve plate and the ring into the interior of the valve body, the stud being secured to the valve body and being threaded into the screw-threaded opening of the boss.

3. A valve for automatically venting air and gas from irrigation systems, comprising a valve body having an air and gas bleed valve and a water flow regulating valve, the bleed valve being supported internally of the valve body by a ring secured coaxially in an outlet, the ring being secured by forming an annular rib on the periphery of the ring which rests on a shoulder formed in the outlet, a seal of cement or the like filling the space between the ring and the interior of the outlet above the rib securing the ring in place, a cylindrical boss supported coaxially of the ring near its lower end by means of a spaced spider extending radially between the ring and boss, the boss being provided with a coaxial internally screw-threaded opening, a circular valve plate having an outer diameter slightly larger than the outer diameter of the ring being adapted to seat against the upper edge of the ring which is machined or ground to a smooth valve seat, a screw-threaded stud

extending through the valve plate and the ring into the interior of the valve body, the stud being secured to the valve body and being threaded into the screw-threaded opening of the boss.

4. A valve for automatically venting air and gas from irrigation systems, comprising a valve body having an air and gas bleed valve and a water flow regulating valve, the bleed valve being supported internally of the valve body by a ring secured coaxially in an outlet, the ring being secured by forming an annular rib on the periphery of the ring which rests on a shoulder formed in the outlet, a seal of cement or the like filling the space between the ring and the interior of the outlet above the rib securing the ring in place, a cylindrical boss supported coaxially of the ring near its lower end by means of a spaced spider extending radially between the ring and boss, the boss being provided with a coaxial internally screw-threaded opening, a circular valve plate having an outer diameter slightly larger than the outer diameter of the ring being adapted to seat against the upper edge of the ring which is machined or ground to a smooth valve seat, a screw-threaded stud

extending through the valve plate and the ring into the interior of the valve body, the stud being secured to the valve body and being threaded into the screw-threaded opening of the boss.

5. A valve for automatically venting air and gas from irrigation systems, comprising a valve body having an air and gas bleed valve and a water flow regulating valve, the bleed valve being supported internally of the valve body by a ring secured coaxially in an outlet, the ring being secured by forming an annular rib on the periphery of the ring which rests on a shoulder formed in the outlet, a seal of cement or the like filling the space between the ring and the interior of the outlet above the rib securing the ring in place, a cylindrical boss supported coaxially of the ring near its lower end by means of a spaced spider extending radially between the ring and boss, the boss being provided with a coaxial internally screw-threaded opening, a circular valve plate having an outer diameter slightly larger than the outer diameter of the ring being adapted to seat against the upper edge of the ring which is machined or ground to a smooth valve seat, a screw-threaded stud

extending through the valve plate and the ring into the interior of the valve body, the stud being secured to the valve body and being threaded into the screw-threaded opening of the boss.

6. A valve for automatically venting air and gas from irrigation systems, comprising a valve body having an air and gas bleed valve and a water flow regulating valve, the bleed valve being supported internally of the valve body by a ring secured coaxially in an outlet, the ring being secured by forming an annular rib on the periphery of the ring which rests on a shoulder formed in the outlet, a seal of cement or the like filling the space between the ring and the interior of the outlet above the rib securing the ring in place, a cylindrical boss supported coaxially of the ring near its lower end by means of a spaced spider extending radially between the ring and boss, the boss being provided with a coaxial internally screw-threaded opening, a circular valve plate having an outer diameter slightly larger than the outer diameter of the ring being adapted to seat against the upper edge of the ring which is machined or ground to a smooth valve seat, a screw-threaded stud

extending through the valve plate and the ring into the interior of the valve body, the stud being secured to the valve body and being threaded into the screw-threaded opening of the boss.

7. A valve for automatically venting air and gas from irrigation systems, comprising a valve body having an air and gas bleed valve and a water flow regulating valve, the bleed valve being supported internally of the valve body by a ring secured coaxially in an outlet, the ring being secured by forming an annular rib on the periphery of the ring which rests on a shoulder formed in the outlet, a seal of cement or the like filling the space between the ring and the interior of the outlet above the rib securing the ring in place, a cylindrical boss supported coaxially of the ring near its lower end by means of a spaced spider extending radially between the ring and boss, the boss being provided with a coaxial internally screw-threaded opening, a circular valve plate having an outer diameter slightly larger than the outer diameter of the ring being adapted to seat against the upper edge of the ring which is machined or ground to a smooth valve seat, a screw-threaded stud

extending through the valve plate and the ring into the interior of the valve body, the stud being secured to the valve body and being threaded into the screw-threaded opening of the boss.

8. A valve for automatically venting air and gas from irrigation systems, comprising a valve body having an air and gas bleed valve and a water flow regulating valve, the bleed valve being supported internally of the valve body by a ring secured coaxially in an outlet, the ring being secured by forming an annular rib on the periphery of the ring which rests on a shoulder formed in the outlet, a seal of cement or the like filling the space between the ring and the interior of the outlet above the rib securing the ring in place, a cylindrical boss supported coaxially of the ring near its lower end by means of a spaced spider extending radially between the ring and boss, the boss being provided with a coaxial internally screw-threaded opening, a circular valve plate having an outer diameter slightly larger than the outer diameter of the ring being adapted to seat against the upper edge of the ring which is machined or ground to a smooth valve seat, a screw-threaded stud

extending through the valve plate and the ring into the interior of the valve body, the stud being secured to the valve body and being threaded into the screw-threaded opening of the boss.

9. A valve for automatically venting air and gas from irrigation systems, comprising a valve body having an air and gas bleed valve and a water flow regulating valve, the bleed valve being supported internally of the valve body by a ring secured coaxially in an outlet, the ring being secured by forming an annular rib on the periphery of the ring which rests on a shoulder formed in the outlet, a seal of cement or the like filling the space between the ring and the interior of the outlet above the rib securing the ring in place, a cylindrical boss supported coaxially of the ring near its lower end by means of a spaced spider extending radially between the ring and boss, the boss being provided with a coaxial internally screw-threaded opening, a circular valve plate having an outer diameter slightly larger than the outer diameter of the ring being adapted to seat against the upper edge of the ring which is machined or ground to a smooth valve seat, a screw-threaded stud

extending through the valve plate and the ring into the interior of the valve body, the stud being secured to the valve body and being threaded into the screw-threaded opening of the boss.

34 is attached coaxially of the valve plate and extends downwardly therefrom to threaded engagement with the tapped boss 28 for manual vertical control of the valve plate relative to its valve seat to regulate the flow of water therebetween. A multiplicity of small perforations 35 are formed vertically through the valve plate preferably in annular arrangement for the passage of air or water through the plate.

A cup of semispherical or other suitable shape is located above and against the upper side of the valve plate 32. The cup is welded or otherwise secured to the plate.

A resilient ball 43, of such density as to be buoyant in water or other liquid with which it is to operate but not to float in air or gas is located in the cup. Rubber and plastic air-filled balls are excellently suited to the purpose. When the ball is enveloped by air or gas it remains at rest in the cup 40 but when immersed in water or other liquid it is buoyed therein and rises from the cup.

A cast, stamped, or otherwise formed, bell-shaped housing 48 is mounted concentrically on the plate 32 and serves to enclose the cup 40 and ball 43. The housing provides a generally hemispherical portion 49, having a circumscribing mounting flange 50 at its lower extremity, and an erect sleeve 51 in its upper portion. The flange 50 has a plurality of openings formed therethrough and a like number of cap screws 52 are extended downwardly through the openings and screw-threadedly engaged in the plate 32. To provide a fluid-tight seal between the housing and the plate, a gasket 53 is provided therebetween.

The cylindrical sleeve 51 is preferably formed integrally with the housing 48 coaxially thereof with the inner end of the sleeve extending inwardly of the inner surface of the housing providing a ball valve seat 56 at its inner end. A plurality of passages 57 are formed radially through the wall of the sleeve 55 exteriorly of the housing for the passage of air or gas from the housing. Dirt, dust, and other foreign matter is prevented from entering the passages 57 by providing external screw threads at the upper terminal end of the sleeve 51. A cap 59 is internally screw threaded at 60 and is screwed onto the upper end of the sleeve with a skirt 61 of the cap extending downwardly in adjacent spaced relation to the portion of the sleeve 51 having the passages 57. Thus, fluids may pass through the passages 57 but the skirt 61 circumscribing the sleeve shields the passages from foreign matter descending thereon.

Operation

The utility and operation of the valve of the present invention is believed to be apparent and is briefly summarized. With the valve mounted in an irrigation T, as shown and described, irrigation water is pumped or otherwise caused to flow into the aqueduct including the T under sufficient gravity or other pressure to be able to rise through the valve. The valve plate 32 is normally closed against the valve seat 33 until manually opened for the passage of water therethrough for irrigation purposes. As the water flows through the irrigation tile 13, air previously contained therein rises through valves of the present invention preferably installed periodically along the length of the aqueduct.

The air is vented through each valve by passing upwardly through the perforations 35, the

housing 48 and exhausting to the atmosphere through the passages 57. The perforations serve to screen dirt and debris in the aqueduct from passing into the housing 48. The ball 43, being heavier than air or gas remains at rest in the cup 40 during venting of air and gas from the housing.

When the venting is completed, water rises through the perforations 35 into the housing causing the ball 43 to be buoyed. When the water has reached a sufficient elevation, the ball is urged into closing engagement against the seat 56 preventing flow of water therefrom. The cup 40 and seat 56 on the lower end of the sleeve 51 are so arranged as to center the ball 43 on the seat.

The ball 43 remains in closed position against the seat 56 as long as water is forced upwardly into the housing 48. When water flow into the aqueduct is terminated, the water in the housing 48 drains downwardly through the perforations 35, the water level recedes, and the ball 43 is gently lowered into the cup 40 in position for successive bleeding and seating operations. The improved valve has been found in actual operation effectively to exhaust air and gas therethrough while spacial adjustment of the plate 32 relative to the seat 33 regulates or blocks, as desired, irrigation water supplied to the stand-pipe. Employment of the valves eliminates the vapor locks previously referred to and minimizes the deterioration of aqueducts of the type described incident to the seeking out of pores, cracks, and the like therein by air and gas.

Although I have herein shown and described my invention in what I have conceived to be the most practical and preferred embodiment, it is recognized that departures may be made therefrom within the scope of my invention, which is not to be limited to the details disclosed herein, but is to be accorded the full scope of the claims so as to embrace any and all equivalent devices and systems.

Having described my invention, what I claim as new and desire to secure by Letters Patent is:

1. An irrigation valve comprising a circular valve seat, a valve plate adapted for fluid tight engagement with the valve seat, screw-threaded means interconnecting the seat and plate for controlled spacial adjustment thereof, said plate having perforations therein, a housing having a port therein mounted in fluid-tight engagement on the plate in covering relation to the perforations, and means contained by the housing for emitting air from the housing and blocking liquid flow therefrom.

2. A combination irrigation valve and bleed valve comprising an annular ring adapted to be mounted axially vertically in an irrigation stand-pipe, said ring having a valve seat formed around its upper edge, a circular valve plate having perforations formed therethrough located over the annular ring movable vertically in a closing and opening relation thereto, means for manually raising and lowering the valve plate relative to the valve seat, a hollow vertical housing secured vertically and coaxially on the valve plate with the perforations of the valve plate communicating with the interior of the housing, an inwardly and downwardly directed bleed valve seat formed interiorly of the upper end of the housing, and a liquid buoyant ball normally resting within the housing below the bleed valve seat movable to closed position against the bleed valve seat in the presence of liquid within the housing.

3. An irrigation valve comprising a circular valve seat, a valve plate adapted for fluid engagement with the seat, screw-threaded means interconnecting the seat and plate for controlled spacial adjustment thereof, said plate having perforations formed therein, a housing having an open upper end mounted in fluid-tight engagement on the plate in covering relation to the perforations, a valve seat integral with the housing circumscribing the opening in the upper end thereof, a resilient buoyant ball adapted to form fluid-tight engagement with the valve seat of the housing when buoyed by a liquid entering the housing through the perforations, and means adapted to retain the ball in substantial alignment with the housing valve seat in the absence of liquid in the housing.

4. A valve comprising a valve seat, a valve plate fitted in fluid tight engagement with the valve seat, said plate having an opening therethrough, means for moving the plate to and from engagement with the valve seat, a housing having a port therein mounted in fluid tight engagement on the plate in covering relation to the opening, means contained by the housing for emitting air from the housing and blocking liquid flow therefrom through the port, and a cap mounted on the housing in shielding relation to the port providing an exhaust opening for the port.

5. A valve comprising a valve seat, a valve 30

plate, means for moving the plate to and from engagement with the seat, said seat and plate defining a continuously open fluid passage therethrough and a discharge opening therebetween closed by movement of the plate to seat engagement, a housing having a port therein mounted in fluid tight engagement on the plate in registration with the fluid passage, and means contained by the housing for emitting air from the housing and blocking liquid flow therefrom through the port.
